PUMP

Kenneth W. Crossman, Willow Grove, Pa., assignor to The Edwin H. Fitter Co., Philadelphia, Pa., a corporation of Pennsylvania

Application August 26, 1943; Serial No. 500,159

6 Claims. (Cl. 103—174)

This invention relates to pumps and has reference more especially to metering pumps of a type designed to displace fluids in relatively small volume and at comparatively low pressures.

In connection with pumps of the kind referred to, I aim to attain, through improved and simplified construction such as hereinafter set forth, the advantages of increased economy in manufacture, and greater reliability in operation with assurance against easy derangement in long continued service and of low cost of maintenance.

Other objects and attendant advantages will appear from the following detailed description of the attached drawings, wherein Fig. 1 is a view in elevation of a pump conveniently embodying the present invention.

Fig. 2 is an axial section of the pump drawn to a larger scale.

Fig. 3 is a view in elevation looking as indicated by the angled arrows III—III in Fig. 2 with portions of the pump casing broken away to expose important structural details within.

Figs. 4 and 5 are sectional views taken as indicated respectively by the angled arrows IV—IV and V—V in Fig. 2.

Fig. 6 is a perspective view of the pump with one of the casing components removed.

Figs. 7 and 8 are perspective views of two disk elements which together constitute the valve means by which fluid flow within the pump is controlled.

As herein shown, my improved pump 10 has a main housing component with a hollow central annular portion 11 from which three cylinders 12 radiate, the hollow 13 of said component being closed by a removable screw-secured cover plate 14. The housing of the pump also comprises a dished supplemental component 15 which is likewise hollow and which has a projection circumferential flange 16 abutted against and screw-secured to a similar flange 17 on the main component 11, the latter flange integrally uniting the cylinders 12. The drive shaft 18 of the pump extends axially into the housing and is journaled in bearing openings 19 and 20 respectively in the wall 21 of the main housing component 11 and in the cover plate 14.

The cylinders 12 are closed at their outer ends by removable heads 22, and screw-plugs 23 in said heads serve as adjustable abutments for the outer ends of compression springs 24 which latter are influential in yieldingly maintaining the pistons 25 in operative engagement with an eccentric actuating cam 26 affixed to the shaft 18 within the hollow 13 of the main housing component 11.

As instanced in Fig. 2, each piston 25 is provided with a pair of oppositely-cupped packing washers 27, 28 which are compressed and held in place by a screw bolt 29.

As shown in Fig. 2 the shaft 18 extends into the hollow 30 of the supplemental housing component 15, and splined to its protruding end for rotation therewith as at 31 is a valve disk 32 which bears against the machined surface 33 of the wall 21 of the main housing component 11 forming the partition between the two hollows 13 and 30, said disk having its circumferential face fitting snugly against the annular wall 34 of said supplemental housing component. From Figs. 5 and 7 it will be noted that the rotary disk 32 has a pair of arcuate slots 35 and 36 arranged in diametrically opposite relation. As shown the slots 35 and 36 are both concentric with the pump axis but at different radial distances therefrom for capacity to register alternately with correspondingly-spaced ports 38 and 39 which form the termini of passages or ducts 40 extending from the outer ends of the respective cylinders 12. Bearing against the rotary disk 32 is a somewhat thicker non-rotating backing disk 41 which is centrally apertured to fit over an axial boss projection 42 on said rotary disk and which like the latter has a snug circumferential fit within the hollow 30 of the supplemental housing component 15. As shown in Figs. 3 and 8, the non-rotating disk 41 is moreover provided in its inner face with arcuate grooves 43 and 44 which are disposed in diametrically opposite relation like the slots in the rotary disk 32 for capacity to alternately register therewith during the operation of the pump. At their corresponding ends the grooves 43 and 44 communicate with ports 45 and 46 having lateral branches 47 and 48 which are internally threaded for reception respectively of outflow and inflow pipes 49 and 50 through which fluid is conducted to and away from the pump. The springs indicated at 51 in Fig. 2 are relied upon to maintain the non-rotating backing disk 41 yieldingly in engagement with the rotary disk 32; and in order that said non-rotating disk may have free axial play within the hollow 30 of the supplemental housing component 15, the circumferential wall of the latter is formed with liberal clearance slots 52 (see Fig. 2) for passage of the outflow and inflow pipes 49 and 50. Gaskets 53 and 54 interposed between the housing parts insure liquid-tight joints at the regions of mutual abutment of these parts. In order that the pump may be conveniently mounted upon or secured to the machine or apparatus with

which it is intended to be used, the supplemental component 15 of its housing is provided with a number of internally threaded bosses 55 as shown in Figs. 1-3.

It is believed that the operation of the pump will be readily understood from Figs. 3-5 without the necessity for further illustration. In Fig. 5, the rotary valve disk 32 is shown in the position which it occupies when the cam 26 is positioned as in Fig. 4 with the shaft rotating clockwise. At this moment the piston 25 at the lower left-hand side of Fig. 4 is moving inward of its cylinder 12 and forcing liquid by way of the passage 40 and port 38, the now registering arcuate slots 35 and 43 respectively of the disks 32 and 41, the port 45 and the passage 47, into the outflow pipe 49. At the same instant the piston 25 at the upper left-hand portion of Fig. 4 is moving outward of its cylinder 12 and drawing in liquid from the inflow pipe 50 via the corresponding passage 40 and port 39, the now registering arcuate slots 36 and 44 of the disks 32 and 41, and the port 46. The piston 25 in the cylinder 12 at the right-hand side of Fig. 4 is at the moment quiescent with both of the ports 38 and 39 of the corresponding passage 40 covered by the blank portion of the disk 32 between the contiguous ends of the arcuate slots 35 and 36 of said disk. Accordingly during each rotation of the shaft 18 a charge of the fluid being pumped is drawn into and expelled from each cylinder 12, the directional flow within the pump being controlled through cooperation between the rotary and stationary disks 32 and 41 whereof the arcuate passages 35, 36 and 43, 44 are so proportioned in circumferential length as to insure continuous displacement of the fluid at a constant pressure and rate. Due to the snug circumferential fit of the disks 32 and 41 within the supplemental housing component 15, and the pressure contact maintained between them and between the disk 32 and the surface 33 of the main housing component 11, by the springs 51, the likelihood of fluid leakage to the exterior is effectively precluded. The springs 51 also serve to take up the wear of the disks 32 and 41, since the latter have the capacity to shift axially on the drive shaft 18 as already explained.

From the foregoing it will thus be seen, my improved pump is not only simple in construction but reliable in operation, and moreover so designed that it can be readily and quickly disassembled in the event inspection or replacement of any of its parts should become necessary after long periods of continuous service.

Having thus described my invention, I claim:

1. In a pump, a housing with a partition setting apart two coaxial juxtaposed annular hollows; a cylinder extending laterally from the housing; a piston within the cylinder; a drive shaft journaled axially of the housing and provided with means within one hollow of the housing for reciprocating the piston; a fluid inlet and a fluid outlet for the pump; and means for controlling fluid flow within the pump including a passageway which leads from the outer end of the cylinder in the partition to a pair of radially-spaced ports open at that surface of the partition exposed within the other hollow of the housing, and a pair of valve disks within the last mentioned hollow, one mounted on the shaft to bear against said surface and having a pair of concentric arcuate slots arranged in di-

ametrically-opposed relation for registry alternately with said ports, and the other disk being non-rotative and bearing against the rotary disk, said non-rotating disk having a pair of concentric diametrically-opposed grooves coincident with the slots of the rotary disk, and ports leading from said grooves respectively to the fluid inlet and outlet aforesaid.

2. A pump according to claim 1, wherein the rotary disk is connected to the shaft with freedom for axial movement thereon; wherein the non-rotating disk has a sliding fit on an axial boss projection on the rotary disk; and wherein a yielding means serves to maintain fluid-tightness between the non-rotating and the rotary disk as well as between the latter disk and the surface of the partition which it abuts.

3. A pump according to claim 1, wherein the rotary disk is connected to the shaft with freedom for axial movement thereon; wherein the non-rotating disk has a sliding fit on an axial boss projection on the rotary disk; and wherein a yielding means serves to maintain fluid-tightness between the non-rotating and the rotary disk as well as between the latter disk and the surface of the partition which it abuts; wherein the fluid inlet and fluid outlet are formed in the non-rotating disk at the edge thereof; wherein inflow and outflow pipes are connected to said inlet and outlet; and wherein the pump housing is provided with clearance slots through which the inflow and outflow pipes pass.

4. In a pump, a housing; a cylinder with a closed outer end connected to the housing; a piston within the cylinder, a drive shaft with bearing in the housing and having means thereon for actuating the piston; a fluid inlet and a fluid outlet for the pump; and means for controlling fluid flow within the pump including a passage leading through a wall of the housing from the outer end of the cylinder to a pair of radially spaced ports in concentric relation to the shaft and open at one side face of the housing wall, and a pair of valve disks, one mounted on the shaft to bear against said wall face and having a pair of concentric arcuate slots in diametrically opposite relation for registry alternately with said ports, and the other disk being non-rotative and bearing against the rotary disk, said non-rotating disk having a pair of concentric diametrically-opposed grooves coincident with the slots of the rotary disk, and ports leading from said grooves respectively to the fluid inlet and the fluid outlet of the pump.

5. A pump according to claim 4, wherein the rotary disk is connected to the shaft with freedom for axial movement thereon; wherein the non-rotating disk has a sliding fit on an axial boss projection of the rotary disk; and wherein a yielding means serves to maintain fluid-tightness between the non-rotating and the rotary disk as well as between the latter disk and the contiguous face of the housing wall.

6. A pump according to claim 4, wherein the rotary disk is connected to the shaft with freedom for axial movement thereon; wherein the non-rotating disk has a sliding fit on an axial boss projection of the rotary disk; wherein the fluid inlet and the fluid outlet are formed in the non-rotating disk at the edge thereof; and wherein inflow and outflow pipes are connected respectively to said inlet and said outlet.

KENNETH W. CROSSMAN.
